(57) **CLAIM**

The ornamental design for a egg separator, as shown and described.

DESCRIPTION

FIG. 1 is a front perspective view of the egg separator;

FIG. 2 is a front elevational view of the egg separator;

FIG. 3 is a rear elevational view of the egg separator;

FIG. 4 is a left side elevational view of the egg separator, the right side elevational view being a mirror image thereof;

FIG. 5 is a top plan view of the egg separator;

FIG. 6 is a bottom plan view of the egg separator; and,

FIG. 7 is a rear perspective view of the egg separator.

The broken lines depicting measuring indicators in the drawings form no part of the claimed design.
